UNITED STATES PATENT OFFICE.

ROBERT W. SCOTT, OF BOSTON, MASSACHUSETTS, ASSIGNOR TO SCOTT & WILLIAMS, INCORPORATED, OF BOSTON, MASSACHUSETTS, A CORPORATION OF NEW JERSEY.

METHOD OF KNITTING SELVAGED FABRICS.

1,148,056.

Specification of Letters Patent. Patented July 27, 1915.

Application filed August 22, 1914. Serial No. 858,137.

To all whom it may concern:

Be it known that I, ROBERT W. SCOTT, a citizen of the United States, and resident of Boston, in the county of Suffolk and State of Massachusetts, have invented certain new and useful Improvements in Methods of Knitting Selvaged Fabrics, of which the following is a specification.

My invention relates to methods of making selvaged knit fabrics of the genus described and claimed in my Letters Patent No. 1,045,621 dated November 26, 1912, and more particularly to making such fabrics by tucking or loop-accumulating operations.

15 In the accompanying drawings, Figure 1 is a diagram face view of the beginning edge of a knit article or fabric made according to my method; Figs. 2, 3 and 4 are diagrams illustrating the relation of the 20 yarns to the knitting needles during the formation of the selvage by one series of operations; Figs. 5 to 8 are illustrations of needles and web-holders showing well known machine devices upon which the new 25 method may be practised; Figs. 9 and 10 are views illustrating the first and second course during a modified series of operations; and Fig. 11 is a view similar to Fig. 1 illustrating the resulting fabric.

30 Heretofore a setting-up course on a single series of naked needles has not been possible without first causing some of the needles to pass beneath the new yarn, as by passing them below the leading stitch cam. I will 35 now disclose a method of forming such a course by causing all of the needles to take yarn and then selectively casting off the 40 yarn from some of them only, preferred devices for practising the method comprising means for tucking by failure to cast off at some of the needles, for instance long latch needles distributed among the other needles.

Referring now to Fig. 2, the operation 45 may be carried out on an endless series of instruments such as latch needles *n*, by laying an initial course 1 in the hooks of all of said instruments, for instance beginning at *a*, this step including if desired the overlapping of said initial course on some of the needles, for instance twice to include the needles 1 and 197 to 200, as shown, the 50 yarn being then passed toward the backs of the needles as at *b*, when it may be severed, or held for introduction at another time.

To provide a fast edge, the initial yarn 1 is now to be so enveloped by the next succeeding yarn that it may serve to lock against raveling the following web. As shown in my said patent, a fast selvage or 60 edge for this purpose ensues when the loops or bights of the next yarn pass recurrently in front of and behind such an initial run or course, and I now provide for so forming such a second course by removing from the 65 hooks of each of a recurrent series of said instruments the bights *d*, Fig. 3, held in said hooks, in any manner, for instance by casting off the bights *d* of alternating needles or groups of needles, as shown at 70 each even-numbered needle, prior to placing a new yarn for course 2 in said hooks. This operation will include passing the cast-off bight *d*, as shown in Fig. 3, behind the 75 needle upon which it was formed.

For the desired purpose of adapting the fabric produced and the steps of its manufacture to production by well-known devices, I may employ for laying the course 1 as described any known form of yarn 80 feeding and other devices capable of laying a yarn on all the needles, beginning at *a* and ending at *b*; and for the ensuing step of casting off the bights of said course at recurrent needles, I may employ any known 85 means for causing some of the needles, as the odd-numbered series, to be positioned or operated in the absence of new yarn, in the same manner as they might be positioned or operated for tucking in the presence of a new yarn. As an instance only I have illustrated in Figs. 5 and 6 representative needles 193 and 194, one series, as that containing needle 193, being provided with long latches *y*, the remaining needles, as 90 194, having shorter latches *x*, as shown in Fig. 6. I may remove the yarn at *b*, and then operate all of the said needles with respect to their customary knocking-over devices, such as web-holders 20, Figs. 5 to 8, 100 so as to retain the bights *d* of the long latch needles when the needles are again retracted, and to cast off the loops of the short latch needles. To aid in this operation, the web-holders 20 may be positioned 105 as shown in Figs. 5 and 6, and in full lines in Fig. 8, to stress the yarn of course 1 against the faces of the short latch needles to close their latches, and to cause the cast-off bights *d* to pass behind the needles as 110

shown in Fig. 3. I now form the second course, beginning at any part of the series of needles as shown at *c*, Fig. 4, by feeding yarn 2 to the hooks of needles now standing recurrently in front of and behind the initial yarn or yarns, and subsequently cast off on to the recurrent loops *w* of yarn 2 the retained bights of yarn 1, Fig. 4. Each of the needles now retains in its hook a stitch 10 *w* or a bight *z* of yarn 2, and course 3 may be knit normally.

The described procedure for course 1 resulted in supplying to the needles yarn interlocked behind recurrent needles so that at course 2 and at subsequent courses the web-holders may be retracted, for their usual function, to the position indicated by dotted lines in Fig. 8, and advance again, as usual. All of the needles, for normal knitting will 20 of course be given sufficient advancing movements to clear both long and short latch needles. Having initiated knitting at all of the needles, I may now knit any desired extent of fabric, which, if desired, may be provided with tucked loops occurring in the wales initiated at any of the loops *z* of the second course.

Referring now to Figs. 5 to 11, I may practice my method by aid of the illustrated 30 machine devices comprising web-holders 20 having upper inwardly sloping surfaces 20^a, and in this case one procedure is as follows: A first course 1 is fed to all of the needles; a second course 2 is then fed while the web-holders are advanced (Fig. 5) the short latch needles being advanced (Fig. 6) and the long latch needles not being advanced (Fig. 5) far enough to clear. The needles are then retracted, thereby casting off course 40 1 at all of the needles having shorter latches *x* while retaining bights *d'* of both course 1 and course 2 at all needles having longer latches *y* (Figs. 7 and 8), the slopes 20^a permitting course 2 to engage beneath the hooks 45 of the web-holders 20. An advance sufficient to clear all the latches of all of the needles is now made prior to taking course 3, during which advance said web-holders remain in the forward position illustrated in full lines 50 in Figs. 6 to 8.

The yarns are now arranged upon the instruments as illustrated in Fig. 10, course 1 being recurrently in front of and beneath the open latches and behind the respective 55 needles. The needles thereafter take yarn for the third course 3, during or after which the web-holders may be operated as usual in the art.

The described steps have resulted in casting off the bights *d'* of courses 1 and 2 on to the bights *w* of course 3, and in casting off 60 yarn 2 at each of the needles having short latches *x*, said short latch needles forming loops *z'* of course 3 in front of the yarn of course 1. The selvage structure of my said

patent is thus formed with respect to the yarns 1 and 3, yarn 2 not being interlooped with or forming a permanent part of the fabric, although said yarn may be retained at the edge of the fabric in some cases by 70 friction.

In each instance described, the steps taken place the initial yarn upon a series of needles, then cast off the bights of said yarn from recurrent needles, and pass said bights 75 behind their needles, prior to causing another yarn to be drawn into loops together enveloping said initial yarn, for the purposes of my said patent. Said steps further comprise operations capable of being performed by movements given in an orderly manner to the knitting instruments, and therefore adapted to automatic machinery organized for this purpose.

What I claim is:

1. The art of knitting selvaged fabrics comprising first forming bights of an initial yarn at each of a series of needles, then casting off said bights at recurrent needles, and thereafter forming a course enveloping said 90 initial yarn.

2. The art of knitting fabrics having a beginning selvage comprising forming bights of yarn on each of a series of needles, then casting said bights from recurrent needles, 95 then passing said bights behind said recurrent needles, and then knitting a second and following courses.

3. The art of knitting selvaged fabrics on a series of needles comprising laying in 100 the hooks of all of said needles an initial run of yarn, then operating upon said yarn at all of said needles to cast said initial run of yarn from recurrent needles and pass said needles in front of their cast-off bights, 105 and thereafter supplying said needles with new yarn and operating them to knit normally.

4. The art of knitting selvaged fabrics on a series of needles comprising laying in the 110 hooks of all of said needles an initial run of yarn, then operating upon said yarn at all of said needles in the absence of new yarn to cast said initial run of yarn from recurrent needles and pass said needles in front 115 of their cast-off bights, and thereafter supplying said needles with new yarn and operating them to knit normally.

5. The art of operating a knitting machine having needles to form a beginning 120 selvage comprising feeding yarn to all of the needles, then operating upon the yarn at some of the needles to retain said yarn, and at other needles to cast off the yarn, and thereafter feeding yarn and operating the 125 needles normally to knit.

6. The art of operating a knitting machine having needles and yarn-feeding devices to form a beginning selvage comprising feeding yarn to all of the needles, then 130

ceasing to feed yarn while operating upon the yarn at some of the needles to retain said yarn, and at other needles to cast off the yarn, and thereafter feeding yarn and operating the needles normally to knit.

7. The art of operating a knitting machine having needles and yarn-feeding devices to form a beginning selvage comprising feeding yarn successively to all of the 10 needles, then repeating the operation at some of the needles, whereby the initial yarn is twice taken at some of the needles, then causing the yarn feeding devices to remove the yarn from the needles while operating 15 some of the needles to retain the yarn, and other needles to cast off the yarn, and thereafter feeding yarn and operating the needles normally to knit.

8. The art of knitting fabrics having selvages on a series of instruments comprising 20 first laying at each of said instruments an initial course, then operating recurrent instruments of said series as for tucking while

operating the remaining instruments as for knitting, whereby the initial course is retained at said recurrent needles and passed behind the remainder; and thereafter operating said instruments for normal knitting in the presence of new yarn during successive courses.

9. The art of operating a knitting machine having needles, web-holders and yarn-feeding devices to form a beginning selvage comprising first forming bights at each of 30 said needles of an initial yarn, and thereafter causing recurrent needles to cast off and advance in front of said bights during maintenance of stress upon said yarn by said web-holders.

In testimony whereof, I have signed my 40 name to this specification in the presence of two subscribing witnesses.

ROBERT W. SCOTT.
